BUOYANT VEST FOR SWIMMERS, WATER SKIERS, AND THE LIKE

Otto W. Githens, Los Angeles, Calif.

Application May 19, 1959, Serial No. 55,977

Term of patent 14 years

(Cl. D71—1)

Figure 1 is a perspective view showing the front and one end of the buoyant vest for swimmers, water skiers, and the like embodying my new design; and

Fig. 2 is a perspective view showing the rear and the opposite end of the same.

I claim:

The ornamental design for a buoyant vest for swimmers, water skiers, and the like, as shown.
